METHOD OF MAKING HELICAL THREAD
RESISTORS

Jacob L. Rector, Belmar, N. J., assignor to the
United States of America, as represented by the
Secretary of War

Application January 4, 1945, Serial No. 571,345

5 Claims. (Cl. 201—67)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to resistors and other electrical resistance devices of the type having terminal ends and means providing a resistive path interposed therebetween. More particularly, the present invention relates to devices of the character referred to which are adapted for use in high voltage circuits and which must be of uniform precision resistance value.

Heretofore, considerable difficulty has been experienced in manufacturing precision resistors of relatively high resistance value. For example, such resistors have heretofore been made by first coating a smooth cylinder of nonconductive material with a resistive material, and then removing a continuous helical strip of the resistive material, leaving a cylinder threaded by the remaining resistive material. Difficulty has been experienced in achieving precision by this method; and due to the small amount of conductive material used, it has further been found difficult to provide uniform linear resistance. Also, resistors so made have been vulnerable to physical injury.

It is, therefore, an object of this invention to provide an improved high resistance device of the character referred to in which uniform precision is attained in construction and resistance value while obviating the above and other constructional difficulties heretofore experienced in the manufacturing of such devices. It is also an object of the present invention to provide an improved method of making a high value resistor whose value may be more readily and accurately determined before manufacturing than has heretofore been possible.

It is a further object of this invention to provide a method of making a high value resistor whose electrical value may be accurately fixed during the manufacturing process.

It is also a further object of this invention to provide a method of making a high value resistor that shall have a uniform resistance per unit length.

It is a further object of this invention to provide a resistor device wherein the resistance element thereof is protected from physical injury, and sufficient dielectric is included between adjacent elements to prevent arcing at high voltages.

It is also an object of this invention to provide a resistor that may quickly and easily be aged and otherwise processed for use.

In accordance with the foregoing objects, I have devised a method of making a high value

2

resistor comprising the steps of providing a body having a surface of nonconductive material with a continuous helical groove thread, coating the grooved surface with a resistive material, and then cutting through the surface coating and below the surface of the nonconductive material a distance that is greater than the thickness of the coating and less than the depth of said groove whereby a thread of resistive material to form a continuous resistor element is spaced between adjacent convolutions of nonconductive material.

For a further understanding of the invention, reference is made to the following description and accompanying drawings for consideration therewith.

15 In the drawing,

Figure 1 is a longitudinal sectional view, partly in elevation, of one embodiment of my invention, representing a preliminary step of manufacture; and

20 Figure 2 is a view, partially in cross section, of a resistor embodying the invention and completely manufactured and ready for use.

Referring to Figure 1, core element 5 comprises a threaded cylinder of nonconductive material. A coating 6 is of any suitable resistive material, such as graphite carried in a binder, which coating completely covers the surface of the core 5. A finish or outer covering 7 of any suitable waterproofing and insulating compound, such as varnish may be applied by spraying or painting over the resistive coating 6. This finish 7 is only applied to the central portion of the cylinder, as will hereinafter appear.

25 As stated above, Figure 1 represents a preliminary step in the manufacture of this embodiment of my invention. After the external thread is cut into the surface of the dielectric cylinder, the coating of resistive material is applied. This coating may be applied by dipping the cylinder into the resistive material, or the coating may be sprayed or painted onto the surface. The finish is then applied and the product at this point is heat-treated.

30 The heat treatment serves two purposes. First, it bakes the resistive coating into a firm unit and hardens the finish, and second, it supplies a series of heat cycles for the purpose of aging the resistor.

35 Referring now to Figure 2 along with Figure 1, the next step in the manufacture of this resistor consists of the operation of turning down the central portion of the cylinder by any suitable means such as a lathe. A radial distance somewhat less than the depth of the thread is taken for the complete cut, thereby removing the tops of the threads and all resistive material above the

depth of the cut and resulting in a central surface length comprising a helically formed strip 8 of resistive material alternating with and contiguous to a helically formed strip 9 of flat topped dielectric. The central portion is then recoated with varnish or other suitable waterproofing and insulating material, as indicated at 10. The coated ends 11, which ends have not been covered with the finish 7, are not turned down and are provided with ferrules 12 and the resistor is ready for use. To insure that the precision desired is obtained, frequent electrical measurements may be made during the turning down process. These measurements, however, are not absolutely necessary, since the proper depth of cutting and length of the central portion between the ferrules can be computed beforehand.

From the foregoing description, it will be seen that a helical resistor element indicated at 18 is disposed in the roots and along the sides of the truncated threads of the core 5 and comprises the part of the coating 6 (Figure 1) remaining after the central portion of the body has been machined between the terminal ends. It will further be seen that this resistor is in the form of a helix whose pitch is determined by the pitch of the thread of the core 5.

Finishing coat 10 comprises a coat of varnish or other suitable material as hereinbefore described and is applied after the turning down process. The whole assembly is now completed and in a form ready for use. Caps 12 are standard terminal ferrules and are pressed on to the ends 11 of the resistor. It will be noted that in this embodiment, electrical contact is made between the caps 12 and the resistor through that part of coating 6 (Figure 1) that was not removed in the turning down process. A tap 14 is provided for picking off an intermediate value of resistance if desired.

The construction described is particularly adapted for use in high voltage, high resistance resistor devices for the reason that the spacing between the threads of resistance material is progressively increased as the depth of the cut in turning down the resistor body, is increased. At the same time the cross sectional area of the resistance element thus formed is decreased, thereby increasing the resistance of the completed resistor. In any case, the object is to provide such a potential gradient along the resistor from end to end, and such spacing between the turns of the resistor element by the interposed nonconducting body formed by the turned-down tops of the threads, that arcing-over does not occur between the turns.

The resistivity of the material applied is such that the required resistance

$$\frac{2RN}{TW}$$

in which $2R$ is the resistance of one turn of differential thickness, N is the number of turns, T is the thickness factor of the material, and W is the width of the resistor path.

Once established by trial, the resistance is brought to the proper value by turning the tops of the threads down to a predetermined diameter. The depth to which the cut is made determines the ultimate resistance, the turning operation decreasing the cross sectional area of the resistance element and increasing the overall resistance set up between the terminal ends of the resistor. The unit is completely heat-treated and varnished or otherwise suitably coated be- 76

fore any adjustment to the final value is made, thus eliminating all danger from injury by handling.

While a present preferred embodiment of the invention has been disclosed and described it is obvious that further modification may be made within the scope of the invention which is pointed out in the appended claims.

I claim:

1. The method of making a resistor comprising the steps of forming a continuous groove into the surface of a body of nonconductive material, coating said surface and filling said groove with a layer of resistive material and then uniformly cutting through said coating and cutting below said surface a distance less than the depth of the groove.

2. A method of making a high value resistor comprising the steps of providing a body having a surface of non-conductive material with a continuous helical groove or thread, and filling the grooved surface with a resistive material, and then cutting through the surface coating and below the surface of the nonconductive material a distance that is greater than the thickness of the coating and less than the depth of said groove, whereby a thread of resistive material to form a continuous resistor element is spaced between adjacent convolutions of nonconductive material.

3. A method of making a high value resistor comprising steps of providing an elongated body of nonconductive material, grooving the body to provide a thread along the body between the ends thereof, coating the body and filling the grooves with resistive material, protecting a restricted central portion of the length with a finish, heat treating the assembly, cutting along said restricted central portion through the coating and body to a uniform depth, which point of depth shall be located between the major and minor diameters of the thread, to form terminal ends, capping said terminal ends with conductive elements in contact with the resistive element, and then applying a second finishing coat.

4. The method of making a resistor comprising the steps of cutting a continuous groove into the surface of a body of non-conductive material, coating said surface and filling said groove with resistive material, heat treating the assembly and then uniformly cutting through said coating and below said surface a distance less than the depth of the groove.

5. The method of making a resistor comprising the steps of cutting a helical thread in the surface of a cylinder of non-conductive material, coating said surface and filling said thread with a resistive material, heat treating said assembly whereby said resistive material will receive a permanent set, and then turning down the surface of said cylinder by a radial distance that is less than the depth of the thread.
